UNITED STATES PATENT OFFICE.

WILLIAM H. SAUVAGE, OF NEW YORK, N. Y., ASSIGNOR, BY MESNE ASSIGNMENTS, TO THE GOULD COUPLER COMPANY, A CORPORATION OF MARYLAND.

SLACK ADJUSTER.

Application filed May 17, 1924. Serial No. 714,166.

This invention relates to improvements in slack adjusters and more particularly to improvements in that type of slack adjusters illustrated and described in my prior United States Patent No. 1,177,213, issued March 28, 1916.

One of the objects of the present invention is to provide an automatic slack adjuster for railway brakes which will be reliable and efficient in use and operation under all conditions.

A further object is to provide a slack adjuster of the above type of durable construction, and having relatively few parts which may be inexpensively manufactured and assembled.

A further object is to provide a slack adjuster of the above type adapted to automatically take up and hold the excess travel of the brake rigging during each complete operation and release of the brakes.

Other objects will be in part obvious from the annexed drawings and in part indicated in connection therewith by the following analysis of the invention.

This invention accordingly consists in the features of construction, combination of parts and in the unique relation of the members and in the relative proportioning and disposition thereof, all as more completely outlined herein.

To enable others skilled in the art so fully to comprehend the underlying features in order that they may embody the same by numerous modifications in structure and relation contemplated by this invention, a drawing depicting a preferred form has been annexed as part of this disclosure illustrating such parts of the truck brake rigging and slack adjuster in side elevation and partly in section as is necessary to understand the invention.

In this drawing, 1 indicates the truck frame provided with a transverse bolster 2, one set of wheels being indicated at 3, with which brake shoes 4 are adapted to co-act. These brake shoes are carried by the usual brake beams 5 and are actuated by the live and dead levers 6 and 7 respectively. The lower ends of these levers are connected by a push rod 8 and the upper end of the live lever 6 is connected by means of a pull rod 10 with the brake actuated mechanism. Associated with the upper pivot 11 of this live lever is a rod 12 having a lost motion de-

vice such as loop 13 at one end to insure brake shoe clearance during the actuation of the slack adjuster. The other end of this rod 12 extends to one side of the truck where it is connected at 14 with a member 15 carrying a temporary take up and holding dog 16 which co-acts with a rod 17 flexibly connected as by means of a chain 18 with the point 20 at the upper end of the dead lever 7.

Supported by the truck frame or draft sill indicated at 21 is a housing 22 comprising two tubular chambers 23, each provided with a plunger and piston 24 and a coiled spring 25, reacting against the end wall 26 of the casing. The rods 27 extend through this end wall and are anchored in the plate 15.

Within the member 22 is a central housing 28 containing permanent holding dogs 29 which co-act with the adjusting rod 17. The holding dog 16 and dogs 29 are preferably rectangular pieces of metal having perforations through which the rod 17 passes and are held at one side against movement while the opposite sides are free to move against the action of springs 30 and 31 respectively, each operating to hold the dogs in normal actuated position or in biting engagement with the rod 17.

Heretofore, as has been explained in my prior patent, the springs 25 were of different strength, but in the present construction greater reliability and efficiency is obtained by making these springs of substantially the same strength whereby the end member 15 moves outwardly in a substantially straight line on application of the brakes when excess travel occurs.

In order that this operation may be more clearly understood, a brief statement thereof is as follows: On application of the brakes the upper end of the live lever 6 moves relatively towards the left a sufficient distance to bring the brake shoes 4 into engagement with the wheels 3. If, however, due to excessive wear of the parts, the live brake lever moves a greater distance than provided for by the lost motion slot 13, then the rod 12 moves toward the left carrying with it the member 15 and the dog 16 slides freely along the rod 17 in that direction only. A movement of the member 15 causes an operation or compression of the springs 25 in both housings.

When the brakes are released the brake

levers are returned to normal position in the usual manner and the springs 25 expand to bring the member 15 back to the position as shown. Inasmuch, however, as the dog 5 16 is not free to slide in a direction relatively towards the right, it grips the rod 17 and moves the same therewith freely through the permanent take up and holding dogs 29 an amount exactly equal to the excess travel of the brake rigging during the preceding application.

In this manner, the slack is taken up from time to time as excess wear occurs until it is necessary to replace the worn brake 15 shoes whereupon the dogs 16 and 29 are tripped by the insertion of any convenient tool into the respective housings and the rod 17 is free to be moved towards the left to its original position. On the first application, after the new brake shoes have been applied, all of the excess slack other than that provided for by the lost motion slot 13 is taken up, first, by the temporary dog 16 and then by the permanent holding dog 29.

25 It will thus be seen that the present invention comprehends a simple and practical device well adapted to accomplish among others all of the objects and advantages herein set forth.

30 Without further analysis the foregoing will so fully reveal the gist of this invention that others can, by applying current knowledge, readily adapt it for various applications without omitting certain features that, 35 from the standpoint of the prior art, fairly constitute essential characteristics of the generic or specific aspects of this invention, and, therefore, such adaptations should and are intended to be comprehended within the 40 meaning and range of equivalency of the following claims.

What I claim is:—

1. In a device of the character described, 45 in combination, brake levers, a permanent take up and holding device associated therewith, comprising a holding rod, a take up dog co-acting with said holding rod, a temporary dog acting upon said rod and freely movable relative thereto on excess travel 50 of the brakes, and two springs of substantially equal tension adapted to be compressed on excess travel and to move the take up rod relative to the permanent take up dog when the brakes are released.

55 2. In a device of the character described, in combination, live and dead levers, a take up rod connected to the upper end of the dead lever, an adjusting rod connected with the upper end of the live lever, temporary 60 and permanent take up mechanisms supported from the truck including two sets of dogs co-acting with said take up rod, one of which acts on excess travel on application of the brakes, and the other of which acts 65 on release of the brakes, and two springs

of substantially equal tension adapted to be compressed for moving the adjusting rod relatively to the permanent take up dogs on release of the brakes.

3. In a device of the character described, 70 in combination, live and dead levers, a take up rod flexibly connected with the upper end of the dead lever, an adjusting rod having a lost motion connection with the upper end of the live lever, permanent and temporary take up and holding means supported from the truck frame and comprising two parts relatively movable to each other on excess travel, yielding connections between said parts including two springs of 80 substantially equal tension adapted to be compressed on excess movement and to expand on release of the brakes, thereby allowing the temporary holding means to act on application of the brakes and the permanent take up means to act on release of the brakes.

4. In a device of the character described, 90 in combination, brake levers, a permanent take-up and holding device associated therewith, comprising a casing having a central housing and a plurality of chambers formed therein, a holding rod extending thru said housing, a take-up dog coacting with said holding rod, a temporary dog acting upon 95 said rod and freely movable relative thereto upon excess travel of the brakes, and springs of substantially equal tension position in said chambers and adapted to be compressed on excess travel and to move the take-up rod 100 relatively to the permanent take-up dog when the brakes are released.

5. In a device of the character described, 105 in combination, live and dead levers, a member supported from the truck frame, comprising a fixed housing and a movable housing associated therewith, a take-up rod flexibly connected with the upper end of the dead lever and extending thru both of said 110 housings, an adjusting rod having at one end a lost motion connection with the upper end of the live lever and being joined at its other end to said movable housing, yielding connections between the housings including 115 springs of substantially equal tension mounted in chambers in said fixed housing, and adapted to be compressed on excess movement and to expand on release of the brakes, a temporary dog in said movable housing 120 adapted to engage said take-up rod upon application of the brakes and being freely movable relative thereto during such excess travel, and a permanent take up and holding dog mounted in said fixed housing and adapted to engage said take-up rod upon 125 release of the brakes.

In witness whereof I have hereunto signed my name.

WILLIAM H. SAUVAGE.
